UNITED STATES PATENT OFFICE.

EDWARD H. WALSH, OF CHICAGO, ILLINOIS.

PLATE-MARKING DEVICE.

Application filed May 26, 1921. Serial No. 472,927.

To all whom it may concern:

Be it known that I, EDWARD H. WALSH, a citizen of the United States, residing at Chicago, in the county of Cook and State 5 of Illinois, have invented certain new and useful Improvements in a Plate-Marking Device, of which the following is a specification.

My invention relates to a device for marking plates as they pass along upon a carrier of any kind, and particularly to apparatus for use in connection with rotary shears used for trimming the edges of plates as they pass through the shears.

In rolling operations it is frequently desirable to roll the sheets into wide strips and then cut the strips longitudinally into narrower widths. Prior to running the sheets through the shears for cutting the narrower strips it is necessary to mark the sheets to guide the operator so that the sheets will be cut to the proper width. Heretofore in doing this kind of work it has been necessary to lay out the lines on the sheets by hand before they pass to the shears and has necessitated an extra amount of work and also because the operation is done by hand it is sometimes not accurate and results in a waste of material. By my improved invention as the sheets are passed through the shears for trimming the edges the plate is marked by my device with a line extending longitudinally thereof and which is easily followed by the operator of the shears which cuts up the sheets into narrower widths. It also enables the sheets to be moved along without delay to the shears and thus the strips are cut up without delay and without the necessary operation of marking, as heretofore explained.

Another and further object of my invention is the provision of an apparatus for making sheets which is simple and efficient in operation and economical in results and which, when set by the operator, is substantially automatic in operation.

These and other objects of my invention will be more readily and better understood by reference to the accompanying drawings, and in which—

Figure 1 is a cross-sectional view through a rotary shearing machine showing my apparatus secured thereto;

Figure 2 is a side view in elevation of the device in place upon the shearing machine and showing the control means used by the

operator to place the device into contact with the sheets;

Figure 3 is a top view of a shearing bed showing the trimming shears and marking 60 device in operation;

Figure 4 is a view showing the plate on the carrier and showing the uneven edges of the plate;

Figure 5 is a detail view of the apparatus 65 showing the scale graduations thereon;

Figure 6 is an end elevational view of one of the marking devices; and

Figure 7 is a side view in elevation of the 70 same device.

Referring now specifically to the drawings, a fixed shear 10 is shown having a frame 11 which is secured to a track 12 by means of a bolt 13, only such portions of the shear 10 being shown as are necessary to 75 illustrate my invention. A movable shear 14 is shown comprising a frame 15 which slides upon the track 12, the rotary shear blade of the movable shear 14 being raised or lowered by the hand wheel 16 to and 80 from the shear 24, in order to adjust the shear blades to various positions to accommodate sheets of varying thickness.

Referring to the fixed shear 10, a rotary shear blade 17 is shown which is mounted 85 upon a shaft 18 extending into the frame 11 of the machine 10 and having at its opposite end any suitable driving mechanism, the shear blade 17 being raised or lowered by the hand wheel 16^a. Mounted upon the 90 outer end of the shaft 18 is a guide roll 19 which is adapted to contact with the sheets on the upper side thereof and hold them as they pass the shearing machine and along the roller bed 28 which forms a conveying 95 table over which the sheets pass. Secured to the frame 11 of the machine is a rotary shear blade 20 power driven in any suitable manner which is just outside of and underneath the rotary shear blade 17 and which contacts with the plate on its under side and forms a part of the shearing mechanism.

The movable shear 14 is substantially like the shear just described and has an upper shear blade 21 mounted upon a shaft 22, driven in any suitable manner and a guide roll 23 on the outer end of the shaft 22. The removable shear 14 is mounted upon and moves along the rail 12 toward and away from the fixed shear 10, this movement being accomplished by a worm gear 105 15^a which engages with a stationary rack 110

(not shown). A rotary shear blade 24 is mounted upon the frame of the machine and serves to hold the material in position under the shearing 21 as the material passes through the shears, the member 24 also being power driven in any suitable manner. A plate 25 is shown passing through the shears and having marginal strips 26 and 27 cut off its sides as it passes through the shears upon the roller bed 28 and being supported by a pair of longitudinally extending members 28^a positioned between the shear blades. Secured to the frame 11 in any suitable manner is a bracket 30, a similar bracket 31 being secured to the frame 15 of the movable shear 14. A shaft 32 is mounted at each of its ends in the brackets 30 and 31 respectively, and extends from the fixed shear 10 to the movable shear 14. The said shaft 32 is round at its end 33 which is mounted on the fixed shear 10 and is square in cross-section for the balance of its length. A bushing 29 is mounted in the bracket 31 so that the shaft 32 will slide therethrough when the movable shear 14 is moved to accommodate sheets of different widths. Secured to the shaft 32 is a pair of marking devices 34 and 35, one of said devices being illustrated in detail in Figures 6 and 7, and each of the marking devices being movable longitudinally of the shaft 32. Each of the marking devices, and of which any number desired may be secured to the shaft 32, consists of a bracket 36, a cap 37 having projections 38 and 39 on each of its sides which fit against projections 40 and 41 integral with said bracket 36 and forming a part thereof, and having bolts 41^a and 42 which pass through the projections 38 and 40, and 39 and 41 respectively, to hold the bracket 36 and the cap 37 in position around a bushing 42^a which is placed upon the shaft 32. The bushing 42^a has collar portions 43 and 44 on each of its ends, the bracket 36 and cap 37 fitting in between the collar portions 43 and 44 of the bushing 42^a. A set screw 45 is inserted through the collar 43 on the bushing 42^a and is in frictional engagement with the shaft 32 so that the marking device may be set in any position at any point along the shaft 32 and held in position. The bracket 36 has a slightly projecting portion 46 which is adapted to co-act with a stud 47 in the collar 44 of the bushing 42^a when the marking device 34 is turned over and out of operative position. Secured to the bracket 36 by means of a pin 48 is a holder 49, the said holder being divided and having a marking element 50 inserted between the end portions of the holder 49, the said marking element 50, such as soapstone or the like, is held in contact with the plate and makes a mark upon said plate longitudinally thereof as the plate passes through the

shear. A thumb screw 51 serves to clamp the member 49 upon the marker 50 so that it is held securely in position to the holder 49. Secured to one end of the shaft 32 is a lever 52 which is connected to a handle 53, the handle 53 being carried by a member 54 which is secured to one side of the shear bed 28. The handle 53 passes through a slot in the member 54 and which has a projection 55 thereon which is adapted to engage in notches 56 and 57 in the handle 53. In case it is desired to lift the markers out of contact with the plate 25 the handle is pulled backward and the projection 55 engages the notch 57 and the lever 53 and thus the markers are held out of contact with the plate, if it is desired to use only one marker the other may be turned by hand upon the bushing 42^a until the portion 46 of the bracket 36 engages the stud 47 so that it is out of contact with the plate as it is passed between the shearing blades and a single marker may be used alone. It may be that in the operation of the shears that plates will be passed therethrough for trimming the edges of the shears without marking them for cutting into narrower strips. The shaft 32 is calibrated, as shown in Figure 5, so that the marking device may be adjusted thereon to different positions on the said shaft and thereby mark the sheets into different widths as they pass through the shears.

In the operation of the device the markers are set at any predetermined point on the shaft 32 by loosening the set screw 45 and sliding the marker to any desired position upon the shaft. Thereupon as the sheet is passed through the shears the handle 53 is pushed forward until the projection 55 engages in the notch 56 in the lever and the marker will, by force of gravity, make a mark extending longitudinally of the sheet as it passes through the shears. A cut-off shear 58 is shown which is adapted to cut the plate 25 into the desired lengths as it passes along in the roller bed 28.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination with a metal working machine comprising a plurality of shearing means spaced from each other, a member spanning the space between said shearing means, means for supporting said member and a marker slidably secured to said member.
2. In combination with a metal working machine comprising a plurality of shearing means spaced from each other, a member spanning the space between said shearing means, means for supporting said member and a marker slidably secured to said member.

means spaced from each other, a shaft spanning the space between said shearing means, means for supporting said shaft upon the said machine and a marker slidably mounted upon the said shaft.

3. In combination with a metal working machine comprising a plurality of shearing means spaced from each other, a member extending transversely across the said machine and spanning the space between the said shearing means, means for supporting said member and markers mounted upon the said transversely extending member.

4. In combination with a metal working machine comprising a plurality of shearing means spaced from each other, a rotatively mounted shaft spanning the space between the shearing blades, means mounted upon the machine for supporting the said shaft at each of its ends and marking members mounted upon the said shaft.

5. In combination with a metal working machine comprising a plurality of shearing means spaced from each other, a rotatively mounted shaft and spanning the space be-

tween the shearing blades, means for supporting said shaft at each of its ends, markers mounted upon the said shaft and means secured to the said shaft, whereby the same may be rotated thereby lifting the markers out of contact with the sheet of metal passing through the said machine.

6. In combination with a metal working machine comprising a plurality of shearing means spaced from each other, a rotatively mounted shaft spanning the space between the shearing blades of said machine, means mounted upon the said machine for supporting the said shaft at each of its ends, a plurality of slidably mounted collars secured to said shaft, rotatively mounted marking numbers carried by said collars, means for rotating the said shaft and a stop on the said collar adapted to engage the marker and lift it out of contact with the sheet of metal passing through said machine.

Signed at Chicago, Illinois, this 13th day of May, 1921.

EDWARD H. WALSH.
